UNITED STATES PATENT OFFICE

2,455,642

WINDOW SASH CONSTRUCTION

Samuel Irvin Baer, Youngstown, Ohio

Application May 24, 1945; Serial No. 595,536

8 Claims. (Cl. 20—49)

1

The present invention relates to improvements in window sash construction and aims generally to improve the construction of window sashes of the type wherein the stiles of the sash are pivotally mounted to and between supports slidably mounted in guides in the window frame, whereby to afford the opening of a single sash or of an upper or lower sash of a window by rotative movement while providing for a vertical upward and downward movement of the sash.

More particularly the invention aims to improve the construction of a window sash of the type disclosed in my prior Patent No. 1,846,704, dated February 23, 1932.

One of the primary objects of the invention is the provision of a window sash and slidable supports therefor having means to interlock the sash and support to effectively prevent the passage of air, moisture and dust therebetween.

A further object of the invention is the provision of improved means for holding the sash and supports under spring tension to prevent rattling of the sash in the supports, which means also is effective to seal the joint around the pivot section to weatherproof the joint.

The above and other objects of the invention will be more fully understood and appreciated by persons skilled in the art from a consideration of the accompanying drawings and annexed specification illustrating and describing a preferred form of the invention.

In the drawings—

Fig. 1 is a fragmental perspective view of a portion of a sash stile and support thereof in disassembled relation, according to one embodiment of the invention;

Fig. 2 is a vertical sectional view of a window showing both window sashes in closed position, an open position being indicated by dotted lines;

Fig. 3 is an elevation of the sash support as viewed from the inner face thereof;

Fig. 4 is a horizontal transverse sectional view of the sash support as taken on the pivot center thereof;

Fig. 5 is a horizontal transverse sectional view of the sash stile as taken on the pivot center thereof;

Fig. 6 is a fragmental perspective view of the sash support;

Fig. 7 is a fragmental perspective view of one of the sash stiles;

Fig. 8 is an elevation of the pivot section and adjoining portion of the sash support with the weatherproofing plate removed;

2

Fig. 9 is a detail perspective view of the resilient weatherproofing plate;

Fig. 10 is a transverse sectional view of a sash stile and cooperating slidable support as taken on a line above the pivot section; and

Fig. 11 is a transverse sectional view of a sash stile and cooperating slidable support as taken on a line through the pivotal axis of the pivot section.

10. Referring more particularly to the drawings, the improved sash construction may be incorporated in a standard type double hung window frame 1 having juxtaposed guides 2 and 3 for the lower and upper sash as will be readily understood.

The improved sash construction of the invention comprises a sash frame including side stiles 4 pivotally connected to cooperating supports 5 therefor, which supports are slidable in the guides 2 or 3 so that the sash may be raised and lowered in the manner of the conventional double-hung sash. Additionally, by pivotally mounting the sash in the slidable supports for rotative movement about a horizontal axis, the sash may be turned so that access to the outer face of the sash may be had from the interior of the building as will be apparent from Fig. 2.

The sash support, in its simplest form, may comprise a bar slidably mounted in the guides 2 or 3 of the frame 1, the outer face of the support being recessed as at 6 for the reception of a sash cord or other sash counter-balancing means (not shown). The inner face of the support 5 is shaped for cooperation with a sash stile and provides an intermediate pivot section 7. Above and below the pivot section 7 the support 5 is rabbeted to provide oppositely facing upper and lower grooved ribs 8 and 9 for interlocking engagement with the stiles 4 of the sash.

40. The opposite faces of the sash stile 4 are rabbeted to provide oppositely facing upper and lower grooved ribs 10 and 11 adapted for interlocking engagement with the support ribs 8 and 9 respectively. The ribs 10 and 11 preferably extend to the upper and lower ends of the sash but terminate short of the center thereof to provide a pivot recess 12 for the reception of the pivot section 7 of the support 5. The end faces of the pivot section 7 and of the recess 12, leading from the outer faces of the support and stile to the grooved sides of the ribs 8, 9, 10 and 11 are beveled so as to form a tight fit when the sash is in closed position. The interfitting faces of the ribs and grooves of the ribs 8, 9, 10 and 11 may be rounded as shown in Fig. 10. Each of the ribs

tapers from the groove outwardly to a rounded nose to facilitate swinging of the stile 4 into interlocking engagement with the support 5 without liability of marring or damaging the ribs.

The supports 5 and stile 4 are provided with transverse bores 13 and 13', respectively, for the reception of a suitable pivot pin 14 and preferably the bores 13 and 13' are disposed slightly below the center of the pivot section 7 and pivot recess 12, as indicated by the line C—C, Figs. 6 and 7, for ease in operating the sash to closed position without damage to the interlocking ribs 8, 9, 10 and 11.

To prevent rattling of the sash and to weather-proof the pivot section and recess against the passage of air, moisture or dust when the sash is closed, I provide a friction plate 15 for the pivot section which may be formed of resilient material such as metal (see Figs. 3, 4, 6, 9 and 11). The friction plate is preferably of a size to cover the pivot section 7 of the support as shown in Fig. 6 and preferably is attached to the support along one edge thereof so that the body of the plate is biased outwardly from the support into tensional engagement with the sash stile 4. This is advantageously accomplished by providing a flange 16 along one edge of the plate 15 which may be anchored in a slot 17 in the support adjacent an outer face thereof.

The plate 15 is adapted to be tensioned in interlocking engagement with the support 5 as well as the stile 4, when the sash is closed, and for this purpose the inner edge of the plate 15 may be headed convexed to provide a bead 18 adapted to be pressed into a groove 19 in the adjoining face of the stile 4. The plate 15 may be formed with one or more beads, or cups 20 adapted to be pressed into a groove 21 in the support 5 to provide a smooth action on the sash stile during opening and closing of the sash as well as to prevent undue wear on the pivot sections 7 and 12. Further weatherproofing of a pivot section may be effected by the provision of a ferrule or bearing 22 on the plate 15 surrounding the pivot 14 and preferably this ferrule 22 is of a length sufficient to extend into the pivot opening 13' of the stile and provide a metal bearing for the stile 4.

From the above it will be seen that the invention improves sash construction of my prior patent from the standpoint of simplicity of construction, economy of manufacture and assembly as well as providing a more effective seal against the passage of air, moisture and dust around the pivot section when the sash is closed.

When the sash is in closed position with reference to the supports the cooperating grooved ribs of the supports and stiles 8—10 and 9—11 will closely interfit making a weathertight joint along the meeting edges above and below the pivot section. The pivot section is effectively weather-proofed by the plate 15 which has one edge anchored in the slot 17 adjacent the outer face of the support 5 while the opposite edge has an oppositely offset portion in the form of a bead 18 pressed into a groove 19 adjacent the inner face of the sash stile 4. When the sash is swung to open position as indicated by the dotted line position shown in Fig. 2, the plate 15 springs outwardly from the support 5 acting to frictionally hold the sash in open position.

Obviously the invention is not to be restricted to the details shown and described as the scope of the invention is best defined by the appended claims.

I claim:

1. A window sash construction comprising spaced supporting members and an intermediate sash member pivoted thereto, said supports and the stiles of said sash member having opposed interlocking grooved ribs extending from opposite ends thereof to a point short of the center thereof to provide therebetween a pivot section surrounding the point of pivotal support, a sheet metal plate mounted in said pivot section and having a single thickness longitudinal flange along one edge thereof embedded in one of said pivoted members and an opposed laterally offset portion along an opposite edge thereof adapted to be pressed within the marginal sides of the other of said pivoted members when the sash is in closed position relative to the supporting member.

2. A window sash construction comprising spaced supporting members and an intermediate sash member pivoted thereto, said supports and the stiles of said sash member having opposed interlocking grooved ribs extending from opposite ends thereof to a point short of the center thereof to provide therebetween a pivot section surrounding the point of pivotal support, a sheet metal plate mounted in said pivot section and having a longitudinal flange along one edge thereof embedded in one of said pivoted members adjacent an outer face thereof and an opposed laterally offset portion along an opposite edge thereof presenting a convexed surface adapted to be engaged by and pressed within the marginal sides of the other of said pivoted members adjacent an inner face thereof when the sash is in closed position relative to the supporting members.

3. A window sash construction comprising spaced supporting members and an intermediate sash member pivoted thereto, said supports and the stiles of said sash member having opposed interlocking grooved ribs extending from opposite ends thereof to a point short of the center thereof to provide therebetween a pivot section surrounding the point of pivotal support, a sheet metal plate mounted in said pivot section and having a longitudinal flange along one edge thereof embedded in said supporting members adjacent an outer face thereof, and an oppositely extending bead disposed adjacent the opposite edge of said plate, the pivot section of said stile being formed with a longitudinal groove to receive said bead when the sash is in closed position relative to the frame.

4. A window sash construction comprising spaced supporting members and an intermediate sash member pivoted thereto, said supports and the stiles of said sash member having opposed interlocking grooved ribs extending from opposite ends thereof to a point short of the center thereof to provide therebetween a pivot section surrounding the point of pivotal support, and weatherproofing means for the pivot section comprising a sheet metal plate formed with a laterally offset flange along one edge thereof, an oppositely extending convexed bead adjacent the opposite edge thereof, one of said members being formed with a longitudinal slot in the pivot section to receive said plate flange and the other of said members being formed with a groove to receive said bead.

5. A window sash construction comprising spaced members and an intermediate sash member pivoted thereto, said supports and the stiles of said sash member having opposed interlocking grooved ribs extending from opposite ends there-

of to a point short of the center thereof to provide therebetween a pivot section surrounding the point of pivotal support, and weatherproofing means for the pivot section comprising a sheet metal plate formed with a laterally offset flange along one edge thereof and an oppositely extending convexed bead adjacent the opposite edge thereof, said sheet metal plate having a pivot-receiving opening and an integral bushing surrounding said opening to provide a bearing for one of said members, the inner face of said supporting members being formed with a longitudinal slot in the pivot section to receive said plate flange and the outer face of the sash member being formed with a groove to receive said head.

6. A window sash construction comprising spaced supporting members and an intermediate sash member pivoted thereto, said supports and the stiles of said sash member having opposed interlocking grooved ribs extending from opposite ends thereof to a point short of the center thereof to provide therebetween a pivot section surrounding the point of pivotal support, and weatherproofing means for the pivot section attached along one edge thereof to one of said members and formed with a plurality of protuberances adapted to be presssed into a groove in the plate-carrying member.

7. A window sash construction comprising spaced supporting members and an intermediate sash member pivoted thereto, said supports and the stiles of said sash member having opposed interlocking grooved ribs extending from opposite ends thereof to a point short of the center there-

of to provide therebetween a pivot section surrounding the point of pivotal support, and weatherproofing means for the pivot section attached along one edge thereof to one of said members and formed with a plurality of half round projections adapted to be pressed into a groove in the plate-carrying member.

8. A window sash construction comprising spaced supporting members and an intermediate sash member pivoted thereto, said supports and the stiles of said sash member having opposed interlocking grooved ribs extending from opposite ends thereof to a point short of the center thereof to provide therebetween a pivot section surrounding the point of pivotal support, and weatherproofing means for the pivot section comprising a sheet metal plate formed with a pivot-receiving opening and a pivot for said supporting and stile member passing through the opening in said plate and disposed at a point removed from the center of the pivot sections of said member.

Certificate of Correction

Patent No. 2,455,642.

December 7, 1948.

SAMUEL IRVIN BAER

It is hereby certified that errors appear in the printed specification of the above numbered patent requiring correction as follows:

Column 4, line 17, claim 1, for the word "member" read *members*; column 5, line 15, claim 5, for "head" read *bead*;
and that the said Letters Patent should be read with these corrections therein that the same may conform to the record of the case in the Patent Office.

Signed and sealed this 19th day of April, A. D. 1949.
